UNITED STATES PATENT OFFICE.

EDWARD F. HILL, OF CHICAGO, ILLINOIS, ASSIGNOR TO A. B. DICK COMPANY, OF CHICAGO, ILLINOIS, A CORPORATION OF ILLINOIS.

DEVICE FOR STENCILING.

1,426,067.

Specification of Letters Patent. Patented Aug. 15, 1922.

Application filed December 9, 1921. Serial No. 521,104.

To all whom it may concern:

Be it known that I, EDWARD F. HILL, a citizen of the United States, residing in the city of Chicago, county of Cook, and State 5 of Illinois, have invented certain new and useful Improvements in Devices for Stenciling, of which the following is a specification.

This invention relates to stenciling and 10 more particularly to a device for imprinting letters, figures or other markings upon a stencil sheet, for reproduction thereby.

It is frequently desired to use figures or letters or other arbitrary markings on a 15 stencil and on prints made therefrom, as for purposes of classification, numbering or identification, or for other purposes, and it is one of the objects of my invention to provide a device whereby a mark, or a series 20 of marks, may be easily and readily impressed upon a stencil sheet for reproduction thereby. Another object of my invention is to provide a device adapted to aid in impressing one or more such marks upon 25 any desired place in a stencil sheet and in symmetrical relation. A further object of my invention is to provide a stencil-imprinting device which is simple, compact and inexpensive in construction, and one 30 which may be readily and easily applied to a stencil sheet when it is desired to use the device therewith, and may be easily and readily removed completely from the sheet when its use is not desired. Other objects 35 will be in part obvious and in part pointed out hereinafter.

In operating with my improved device upon such a stencil sheet, I preferably place the sheet upon a flat rigid plate so as to provide 40 a suitably rigid backing surface beneath the sheet. In accordance with my invention I provide an impression implement, preferably comprising a rigid bar having a metallic type in relief on one end thereof 45 and adapted to be taken in the hand and thrust against the stencil sheet to cause the impression of the type to be imprinted upon the stencil sheet, for reproduction on prints made from said sheet. By this means the 50 imprint of any letter, figure or other marking may be cut into the stencil sheet in accordance with the particular type face used. In order to aid the operator in directing the type with sufficient force against a desired 55 spot on the sheet I provide a carriage having a guideway adapted to receive the im-

pression bar for reciprocation therein. The carriage is adapted to be placed on a stencil sheet with the guideway extending in a perpendicular direction toward the surface 60 of the stencil sheet. The impression bar is slidable vertically in said guideway and is adapted to be thrust with a quick movement of the hand against the stencil sheet to cause the type to leave its imprint therein. The guideway directs the type against the desired spot on the sheet, steadies the movement of the implement and insures proper alignment of the type face with the surface of the stencil sheet. 65

If desired, I mount my carriage upon a T square so as to be slidable in longitudinally disposed grooves thereon. When a T square arrangement is used the stencil sheet is preferably mounted upon a support presenting 70 squared, rectangular side and end members against which the head of the T square may abut. This arrangement aids in placing a series of marks in linear alignment on the sheet. The T square may be scaled so that 75 a series of marks may be accurately spaced as desired. The use of my improved device embodying the T square is especially suitable for use with devices for making tracings or copies of drawings of the character 80 disclosed in the patent to Albert B. Dick, "Apparatus for drawing on stencils," No. 1,163,647, in which the stencil sheet is supported upon a transparent table top positioned over a source of light, the transparent 85 top being surrounded by a frame which is squared for the purpose of accurately guiding a T square. 90

In order that a clearer understanding of my invention may be had, attention is hereby directed to the accompanying drawings forming part of this application and illustrating certain possible embodiments of my invention. Referring to the drawings, Fig. 1 is a sectional view of the carrier positioned on a supported stencil sheet with the impression implement positioned in the carrier; Fig. 2 is a top plan view of the carrier on a supported stencil sheet showing, diagrammatically, letters impressed on the 100 sheet; Fig. 3 is a perspective view of an impression implement; Fig. 4 is a top plan view of my impression implement mounted in a carrier which is associated with a T square resting upon a supported stencil 105 sheet; Fig. 5 is a vertical section taken on the line 5—5 of Figure 4, the carrier and im- 110

pression implement being shown in plan; and Fig. 6 is a vertical section taken on the line 6—6 of Figure 4. Similar reference characters designate similar parts throughout the several views of the drawings.

Referring to the drawings, a stencil sheet 1, provided with the usual backing sheet 2, is shown supported upon a flat, rigid surface 3 of a support 4. The support may suitably 10 comprise a flat piece of wood, metal, glass or other suitably rigid material, the only essential requirement being that a flat and rigid backing be provided underneath the stencil sheet 1. The stencil sheet and its 15 mounting forms no part of my invention. As shown in Fig. 3, I provide an impression implement comprising a rigid bar 5, preferably of metal, provided at one end with a metallic type 6. The type may be of the ordinary relief form and is preferably cast in the ordinary manner. If desired, the type 20 6 may be cast in a small type bar 7, comprising a suitable metal or alloy, and the type bar 7 then soldered or otherwise attached, as at 8, to the end of a bar 9 of firmer and heavier material, such as brass. The bar 5 is adapted to be grasped in the hand and the type 6 thrust against the surface of the stencil sheet 1 with a quick, firm 25 30 movement so that the type will cut its impression upon the stencil sheet for reproduction when copies are made in the regular manner from the stencil.

In order to make it easier to properly 35 imprint the type at any desired place on the stencil sheet, I provide a carriage 10 adapted to rest upon the stencil sheet and adapted to guide the impression implement 5. As shown, this carriage comprises a flat, 40 rectangular frame 11 adapted to lie flat upon the surface of the stencil sheet 1. Extending upwardly from the top of frame 11, and substantially at right angles to the plane thereof, are two members 12, 45 each substantially in the form of an inverted U, their ends being attached to the frame 11, as by means of rivets 13. The frame 11 has a central open portion and the members 12 are arched thereover. Supported 50 by and between the two members 12 is a tube 15 of rigid material such as metal, which may be soldered or otherwise secured to members 12 as at 14. Preferably, the impression implement 5 is square in cross 55 section and the passageway through the tube 15 is also square and just large enough to permit the impression bar 5 to be freely reciprocated vertically therein and at the same time preventing the turning of the bar. 60 The tube 15 is positioned so as to be perpendicularly disposed to the plane of the frame 11, and in consequence will be perpendicularly disposed to the surface of the stencil sheet 1 when the carrier 10 is positioned thereon. Thus the type face is held

in proper alignment with the surface of the stencil sheet, and will be properly guided and steadied for easy operation.

I preferably provide a plurality of impression implements 5 carrying, respectively, 70 the various letters, numbers or markings to be applied to stencil sheets. Each impression implement may carry one type character 6, or each bar may be supplied with two characters, one at each end of the implement. In operation, the carriage 10 is placed upon the surface of a supported stencil sheet with the hollow of the tube 15 pointing perpendicularly toward the spot on the sheet at which the imprint of the type is desired to 75 80 be made. The impression implement carrying the desired type is then taken and placed in the guide tube 15 with the chosen type directed toward the stencil sheet. The impression implement is then raised a distance in the guide 15 and then thrust downwardly against the stencil sheet 1 with a quick motion of the hand, and with such force as is required to cause the type character to be satisfactorily imprinted on the 85 90 stencil sheet. By moving the carriage to desired places on the sheet, and repeating the printing operation with chosen type, a series of marks may readily and easily be impressed upon the stencil sheet for reproduction thereby. As shown in Figure 2, 16 represents diagrammatically various characters successively impressed upon the stencil sheet 1 by the use of my improved device.

By combining the carriage 10 with a T 100 square I am able to provide a device whereby accurate alignment and spacing of the letters imprinted upon the stencil sheet may be obtained. As shown, in Figures 4, 5 and 6 the T square used comprises a head 105 portion 17 having a downwardly extending flange 18 adapted to abut against a straight edge of the supporting plate 4 upon which the stencil sheet is mounted, and a straight body portion 19 adapted to extend across the 110 surface of the stencil sheet. The body portion 19 has a longitudinal central opening as at 20 and is provided with inwardly facing grooves, as at 21, running longitudinally from the head of the T square to the outer 115 end of the body. The flanges 22 of the frame member 11 of the carriage 10 are adapted to fit into the grooves 21 whereby the carriage is supported upon the T square. and is adapted to be slid back and forth 120 along the portion 19 with the guideway for the impression implement 5 over the opening 20. The T square is preferably marked to scale as at 23, the scale being on the upper side of the member 19 and extending 125 along for approximately the length of the opening 20. In operating this T square device with the carriage slidably mounted in the grooves 21, the T square is placed over a stencil sheet in suitable position. The car- 130

riage may then be moved linearly to cause successive type impressions to be arranged in linear alignment upon the stencil sheet. By aligning the carriage with appropriate scale markings the spacing between the characters printed may be accurately predetermined. The T square device greatly aids the ease and accuracy in which a series of markings may be placed upon a stencil sheet in symmetrical relation. The carrier having the guideway for the impression implement being movable on the T square, which is itself movable over the stencil sheet, a series of marks may be easily, quickly and accurately impressed upon the stencil sheet at any desired places on the sheet, and in any desired relation to each other.

After the desired markings have been placed on the stencil sheet, the device may be readily and easily lifted from the sheet and laid aside until its use is again desired. The stencil sheet may, of course, be operated upon further by other means, if desired. For instance, if my invention has been used merely to place a title or an identification marking upon the stencil, the body of the stencil may be cut by means of a typewriter, or a stylus, or by other means.

It is to be understood that any desired form of manually operable impression implement may be used, and that the form of the carriage or of the T square may be modified and changed considerably without departing from the scope of this invention.

It is intended that all matter contained in the above description or shown in the accompanying drawings shall be interpreted as illustrative and not in a limiting sense.

40 What I claim is:—

1. A device for cutting stencils, comprising, in combination, an impression implement having type and adapted to be manually directed against the surface of a stencil sheet to cut an impression of said type therein, and means, comprising a movable frame providing a guideway for said implement, for guiding said type against the surface of said stencil sheet when said implement is operated.

2. A device for cutting stencils, comprising, in combination, a frame adapted to be placed on the surface of a stencil sheet, a guideway on said frame disposed perpendicularly to the surface of said sheet, and an impression implement mounted in said guideway and adapted to be moved manually therein and against the surface of said stencil sheet to cut an impression of said type therein.

3. A device for cutting stencils, comprising, in combination, a frame adapted to be placed on the surface of a stencil sheet, a guideway on said frame disposed perpendicularly to the surface of said sheet, and

an impression implement mounted in said guideway and adapted to be moved manually therein and against the surface of said stencil sheet to cut an impression of said type therein, said frame being movable over the surface of said stencil sheet whereby said implement may be guided against any predetermined part of said surface.

4. A device for cutting stencils, comprising, in combination, an impression implement adapted to be directed perpendicularly against the surface of a stencil sheet to cut a stencil, and a carrier adapted to rest upon the surface of said stencil sheet and having a guideway for said implement extending perpendicularly to the surface of said sheet, whereby movement of said implement in said guideway is restricted to movement which is directionally perpendicular to the surface of said sheet.

5. A device for cutting stencils, comprising, in combination, a T square having a pair of longitudinally extending grooves and an aperture between said grooves, a carrier having a pair of flanges seated respectively in said grooves whereby said carrier is maintained slidably in position on said T square, an impression implement comprising a rigid bar carrying type, and a guiding-member for said implement supported on said carrier whereby said implement is restricted to movement perpendicular to the plane of said T square.

6. A device for cutting stencils, comprising, in combination, an impression implement angular in cross section and having type, and adapted to be manually directed against the surface of a stencil sheet to cut an impression of said type therein, and means, comprising, a frame movable over said stencil sheet and having a guideway for said implement and conforming to the shape thereof, for guiding said type against the surface of said stencil sheet and preventing rotation of said implement in said guideway when said implement is operated.

7. A device for cutting stencils, comprising, in combination, a T-square movable in either of two opposite directions over a stencil sheet, a carrier for an impression implement slidably mounted on said T-square for movement in either of two opposite directions at right angles to said movement of said T-square, said carrier having a perpendicularly disposed guideway for an impression implement and an impression implement mounted for manual reciprocation in said guideway and having type, and adapted to be directed against the surface of said stencil sheet to cut an impression of said type therein at predetermined places determined by the adjustment of said T-square relatively to said sheet and to the adjustment of said carrier relatively to said T-square.

21

8. In stenciling apparatus, a stencil sheet, a support for said sheet having a straight edge portion, a T-square having a head portion providing with a flange abutting said 5 straight edge and an arm extending over said stencil sheet, said arm having a central opening and inwardly facing grooves along said opening, a carrier slidably mounted in said grooves and having a perpendicular guideway directed toward said 10

opening, and an impression implement mounted in said guideway for reciprocation toward and from said stencil sheet to cut an impression therein.

This specification signed and witnessed 15
this 6th day of December, 1921.
